WALTER HAMILTON, OF NEW YORK, N. Y., ASSIGNOR TO THE ACME
MINING MACHINE COMPANY, OF SAME PLACE.

METAL-EXTRACTING APPARATUS.

SPECIFICATION forming part of Letters Patent No. 311,748, dated February 3, 1885.

Application filed April 30, 1884. (No model.)

To all whom it may concern:

Be it known that I, WALTER HAMILTON, of New York, in the county and State of New York, have invented a certain new and useful Improvement in Metal-Extracting Apparatus, of which the following is a specification.

My invention relates to apparatus for the extraction of metals from their ores by the lead-bath process—that is, by the amalgamation of the metal contained in the ore with molten lead; and it has for its object the complete distribution of the ore as it passes through the lead, so that every portion of it will be exposed to contact with the lead, and so that it will not be exposed to oxidation in its passage.

In carrying out my invention I feed the crushed ore into an open chamber submerged in and filled with the lead, which carries the ore from one end of the kettle to the other, and is so arranged that the ore carried by it is spread out or distributed in its passage. At the discharge end of the kettle the refuse rises from the chamber to the discharge. I employ a series of these chambers, moving successively through the lead, and each carrying a portion of the ore from one end of the kettle to the other, and delivering the refuse to the discharge.

The series of open chambers is arranged in the form of a cylinder revolving in the lead. I prefer to have this cylinder completely submerged in the lead, and to employ a suitable intermittently-operating feeding device, which will deliver successive portions of the ore to each chamber as it passes the feeding end, when such chamber will carry the ore down and then up again. As the chamber moves, it being filled with the lead, the ore, being buoyant in the lead, constantly changes its position in the chambers, and is thus spread out and distributed during the passage.

Instead of using a feeding device, I may so place the cylinder that the top of it is above the lead, and the ore being placed upon the surface of the lead at the feeding end, the chambers pass through it and each takes in a portion of the ore to carry it around to the discharge; or one cylinder may carry the ore

around and then deliver it to another, which will immerse it again and carry it to the discharge.

My invention is illustrated in the annexed drawings, in which Figure 1 is a longitudinal section of an apparatus embodying the preferred form of the invention; Fig. 2, a transverse section of the kettle with the distributing apparatus in elevation; Fig. 3, a plan view of the apparatus, the adjustable discharge-plate and the plunger being omitted for clearness; Fig. 4, a view of the cylinder, partly in plan view and partly in section; Fig. 5, a section of a part of the cylinder; Fig. 6, a sectional view of an apparatus having the same cylinder, with a different form of feeding device; Fig. 7, a section of an apparatus in which the cylinder is self-feeding; and Fig. 8, a section of an apparatus employing two cylinders.

A is a suitable kettle. It has a cover consisting of a curved central portion, B, an inclined part C at one end, and an adjustable inclined part D at the other, and side walls, E E, on each side of its parts B C D. The part C forms with the inclined side of the kettle beneath it a feeding-passage, and part D similarly forms a discharging-passage. The cover has exterior flanges, upon which it is supported, as shown, so that it is readily removable to reach the interior of the kettle. Under the middle portion, B, of the cover the cylinder revolves. This cylinder is an open cage, consisting of a central hub, a, placed on a shaft, b, end plates, b' b', connected by cross-bars d d and radial plates c c, each extending from the hub to the edge of one of the cross-bars d, and thus dividing the cylinder into a series of open chambers. The radial plates are rifled on both sides, as shown. When the cylinder is immersed in the molten lead, these chambers are of course filled with it. The end plates have one or more apertures, d', for each chamber. The surface-line of the lead in the kettle is indicated by the dotted line xx. The shaft b is supported in bearings at the ends of rods e e, which pass through tubular bearings f f on the inside of walls E E of the cover, and are adjustable in such tubular bearings by turning nuts e' e', so that

the cylinder can be raised or lowered to adjust its position relative to the cover. A worm-wheel, *g*, is on shaft *b*, and engages with worm *h*, which passes through the long tubular bearing *i*, supported upon the cover, and is revolved by pulley *k* or by any suitable gearing from any source of power. Part *D* of the cover is hinged at *l*, so that its inclination can be adjusted to change the angle at which 10 the material rises to the discharge according to the different specific gravities of the various ores which may be used. A screw, *m*, passing through a lug on one of the side walls *E*, serves as an adjustable stop to hold the 15 plate *D* at the angle at which it is placed, keeping it from being pressed back by the lead. The hinged plate *D* is omitted in Fig. 3 for clearness.

All the parts of the apparatus, being supported by the movable cover, can be readily taken out from the kettle.

Referring, now, more especially to Figs. 1, 2, and 3, *F* is a plunger (omitted in Fig. 3) for feeding the ore to the distributing-chambers. Ribs or flanges *n* are formed upon the under side of inclined part *C* of the cover, forming guides for the plunger, and these ribs extend around to the inner side of curved part *B* on both sides of the revolving cylinder, 25 forming a kind of pocket for the ore fed down by the plunger. The plunger *F* is tubular, and a rod, *G*, extends through it, carrying at its lower end a face-plate, *o*, for the plunger. This face-plate is moved out quickly when 30 the plunger reaches its lowest point to shake off the ore and prevent the plunger from drawing back any of it in its return movement. Plunger *F* and rod *G* are connected with any suitable source of motion.

40 The operation of the apparatus is as follows: The kettle being filled with the melted lead, which also fills all the distributing-chambers of the revolving cylinder, the plunger *F* is forced down, delivering a portion of the ore 45 to the chamber which is at that point of the kettle. This chamber moves on down and up again, and as it continually changes its inclination the ore in it continually changes its position, as shown, being constantly buoyed up 50 by the lead, and is thus distributed, so that every part of it comes into contact with the lead. The ore thus spreads itself up one side of one of the radial plates as the cylinder carries it down, and up the opposing side of an 55 adjacent plate as it rises. Both sides of each plate thus act on the ore, and it is thereby most effectually distributed, the riffles on the plates assisting the distribution. No apparatus has heretofore been used in which this action 60 could occur, the ore never before having been placed between two radial plates. When the chamber rises as far as the hinged plate *D*, the opening of the chamber is above the material in it from which the metal portion 65 has been removed during the passage, and such material or tailings therefore rises through said opening and passes up to the

discharge. The cylinder is adjusted to bring it close to the cover, so that said cover forms a scraping-surface, and the ore, when fed 70 down, cannot pass above the cylinder, but must enter the chambers. The plunger delivers a portion of ore to each chamber successively as they pass, and each chamber carries it around and delivers it in the manner just described. 75 Such portion of the lead in the chamber as is displaced by the entrance of the ore escapes through the apertures *d* in the end plates. By having a hub, *a*, instead of letting the radial plates extend from a center, the ore is 80 prevented from being crowded into angles, from which it could not readily escape. It will be seen that the kettle is completely covered, except at the feeding and discharging openings, which are filled by the ore and 85 refuse, so that the lead is nowhere exposed to oxidation.

In Fig. 6 is shown the cylinder, constructed, as already described, with the intermittently-operating feeding device, set forth in an application made by me of even date herewith. 90 This device is a rocking plate, *H*, having a curved end, *p*, which plate is pivoted at *r*, and is moved by means of a rod, *I*, connected with the source of power. In this view the 95 kettle and portions of the cover are omitted, being the same as are shown in the preceding figures, except that the kettle is extended at the feeding end to give room for the feeding-plate. The plate *H* rocks down, carrying with 100 it a portion of the ore, and in its descent the ore spreads itself along the plate, and finally all rises to one of the chambers in the cylinder, which carries it to the discharge end of the kettle, as previously explained. The plate 105 *H* rocks up and down, bringing down fresh supplies of ore to the different chambers as the cylinder revolves.

In Fig. 7 the cylinder is not wholly submerged, a portion of it extending above the 110 surface of the lead, and as it revolves entering the ore accumulated at the feeding end, so that each chamber takes in some of the ore and carries it down. The cylinder is similarly 115 constructed, supported, and revolved as before. In this form of the apparatus the cover is differently constructed, having a vertical partition, *J*, which, with part *C*, forms a kind of hopper, in which the ore is placed. While this partially-submerged and self-feeding cylinder is in some cases a desirable and convenient apparatus, I prefer, usually, to have the distributing-chambers entirely submerged, and employ a device for feeding the ore down 120 to them. I may, however, employ both forms together, as is illustrated in Fig. 8. Here the self-feeding cylinder carries the ore to a smaller but similarly-constructed cylinder, *K*, which carries it down again and delivers it to the discharge. By thus passing the ore 125 through two cylinders, or more, if desired, its angle of movement is changed again and again, and consequently it is better distributed.

I am aware that in apparatus for the pur-

pose described a revolving cylinder has been employed having corrugations or flanges upon its surface, in which corrugations or flanges the ore was intended to be carried down through the lead to rise again on the other side. An example is the patent of Taylor, No. 253,785. In such a device, however, there is no opportunity for the ore to change its position or spread itself out, but it becomes packed in by the pressure of the lead, so that not only is it not brought into complete contact with the lead, but it is prevented from rising.

It is evident that the devices herein described and claimed are applicable to a mercury process of amalgamation, although I prefer to use the lead-bath process. I am also aware of the employment as a feeding device of a series of cups or buckets, which carried the ore to the bottom of the kettle, from whence it was allowed to rise through the liquid—as, for instance, in the patent of Vanderhoof, No. 283,540. Such buckets, however, are not "distributing-chambers," for in them the ore is always in the same position, being packed in and not allowed to be scattered or separated in its passage, the distribution of the ore being accomplished as it rises after leaving the buckets. I am not aware that distributing-chambers have ever been used to convey the ore through the amalgamating-liquid in which the ore was allowed to be scattered or distributed during its passage.

What I claim is—

1. In extracting apparatus of the character described, the combination, with the kettle, of an open distributing-chamber traveling longitudinally in the kettle, whereby the material is conveyed through the liquid from the feeding end toward the discharge, substantially as set forth.

2. In extracting apparatus of the character described, the combination, with the kettle, of a series of open distributing-chambers traveling in succession longitudinally through the kettle, whereby successive portions of the material are carried through the liquid from the feeding toward the discharge, substantially as set forth.

3. In extracting apparatus of the character described, the combination, with a kettle, of an open distributing-chamber constantly submerged in the liquid of the kettle for conveying the ore through the liquid, and a feeding device for conveying the ore beneath the surface of the liquid to said chamber, substantially as set forth.

4. In extracting apparatus of the character described, the combination, with a kettle, of a series of distributing-chambers for conveying the ore through the liquid of the kettle, and an intermittently-operating feeding device for feeding portions of ore successively to the chambers, substantially as set forth.

5. In extracting apparatus of the character described, the combination, with a kettle, of

a cylinder revolving in a direction parallel with the length of the kettle, having open distributing-chambers for conveying the ore through the liquid of the kettle, substantially as set forth.

6. In extracting apparatus of the character described, the combination, with a kettle, of a revolving cylinder entirely submerged in the liquid of the kettle, having open distributing-chambers for conveying the ore through the liquid, and an intermittently-operating feeding device conveying portions of ore successively to the chambers, substantially as set forth.

7. In extracting apparatus of the character described, the combination, with a kettle, of the revolving cylinder entirely submerged in the liquid, having open distributing-chambers for conveying the ore through the liquid, and a plunger for conveying portions of the ore successively to the chambers, substantially as set forth.

8. In extracting apparatus of the character described, the combination, with a kettle, of two or more cylinders revolving within said kettle, each having distributing-chambers, the first of which delivers the ore to the next, and so on, if more than two are used, substantially as set forth.

9. In extracting apparatus of the character described, the combination, with the kettle, of the cylinder revolving in the liquid of the kettle, divided into open radial chambers, and having one or more outlets for each chamber at the ends of the cylinder, substantially as set forth.

10. In extracting apparatus of the character described, the cylinder having end plates, and radial plates dividing it into chambers, and one or more apertures in the end plates for each chamber, substantially as set forth.

11. In extracting apparatus of the character described, radial plates, each having a continuous surface, between which the material is carried through the liquid, substantially as set forth.

12. In extracting apparatus of the character described, radial plates rifled in both sides, between which the material is carried through the liquid of the kettle, substantially as set forth.

13. In extracting apparatus of the character described, the combination, with the kettle, of the cover forming a scraping-surface for the ore-conveying devices, substantially as set forth.

14. In extracting apparatus of the character described, the ore-conveying cylinder, adjustable vertically relative to the cover, substantially as set forth.

15. In extracting apparatus of the character described, the combination, with the kettle having a cover and the cylinder revolving beneath said cover, of the ribs or flanges on the inner side of the cover, forming a pocket enclosing the upper part of the cylinder, substantially as set forth.

16. In extracting apparatus of the character described, the combination, with the kettle and the cover having ribs on its under side, of the plunger moving between said ribs for 5 delivering the material to the liquid in the kettle, substantially as set forth.
17. In extracting apparatus of the character described, the combination, with the kettle, of the plunger for delivering the material to the 10 liquid in the kettle, said plunger having a movable face-plate, substantially as set forth.
18. In extracting apparatus of the character described, the combination, with the kettle, of the tubular plunger for delivering the material to the liquid in the kettle, and the rod extending through said plunger, and carrying a 15 face-plate at its end, substantially as set forth.
19. In extracting apparatus of the character described, the combination, with a kettle having a discharge-opening, through which the refuse rises, of means for varying the angle at 20 which it rises, substantially as set forth.
20. The combination, with the kettle which contains the amalgamating-liquid, and devices for conveying the material through the liquid 25 to the discharge, of a hinged plate forming one side of the discharge-way, substantially as set forth.

This specification signed and witnessed this 25th day of April, 1884.

WALTER HAMILTON.
